UNITED STATES PATENT OFFICE.

WILLIAM S. WITTEN, OF CHICAGO, ILLINOIS.

CAR-DOOR LOCK.

Application filed March 3, 1922. Serial No. 540,687.

To all whom it may concern:

Be it known that I, WILLIAM S. WITTEN, a citizen of the United States, and a resident of Chicago, in the county of Cook and State 5 of Illinois, have invented certain new and useful Improvements in Car-Door Locks, of which the following is a specification, reference being had to the accompanying drawings.

10 My invention relates to locks for car doors and has for its object to provide an improved gravity-operated combined latch and lock for such doors which will be arranged so that a car seal may be readily applied there-
15 to, and which will be self-lubricating so that it will not be apt to get out of order through exposure to the elements; also to provide a device of this character which may be used on doors arranged to swing laterally as well
20 as to move endwise, and to provide means by which the latch may be secured either in its operative or in its inoperative position. I accom-
plish this object as illustrated in the drawings and hereinafter described. What
25 I regard as new is set forth in the claims.

In the accompanying drawings,—

Fig. 1 is a side view of part of a freight car showing my improved lock and latch applied to the door thereof;

30 Fig. 2 is a side view of the lock, the cover plate of the case being removed and some parts being in section;

Fig. 3 is a vertical section on line 3—3 of Fig. 2;

35 Fig. 4 is a view similar to Fig. 2 showing some modifications;

Fig. 5 is a perspective view of the locking device used in the arrangement shown in Figs. 2 and 3; and

40 Fig. 6 is a perspective view of the locking device shown in Fig. 4.

Referring to the drawings,—7 indicates the side of a freight car, 8 the usual sliding door thereof suspended by hangers 9 from a rail 10, and 11, 12, 13 the side and bottom panels of the car door frame.

14 indicates the casing of my improved lock and latch, and 15 the latch member mounted therein. This latch member com-
50 prises an intermediate portion or hub 16 which is mounted upon a pivot 17 mounted in the side members of the case near the lower margin thereof, as best shown in Fig. 2. From this hub 16 extends a shank 18
55 having a head 19, the lower portion of which

is extended downward to form a lock or latch bolt 20. The head 19 is also provided with an upwardly-extending rib or projection 21 adjacent to its outer margin, the purpose of which will be hereinafter set forth. Extending from the hub 16 at an obtuse angle with the shank 18 is an operating arm 22 which projects through an opening in the case so that it is conveniently accessible for operation by hand. As shown in Fig. 2 the head 19 is provided with a shoulder 23 adapted to bear on the lower margin of the case and form a stop to limit the downward movement of the head 19 and bolt 20. When the latch is in its normal position the bolt 20 extends down through an opening in the lower margin of the case so that it is adapted to engage a keeper 24 secured in the proper place to receive it. Preferably this keeper has a recess 25 in which the bolt 20 fits, and at one side of said recess is a bevelled guide block 26 which projects out from the side of the car so that when the door has been swung away from the side of the car, as indicated by dotted lines in Fig. 3, the rounded lower margin 27 of the bolt 20 is adapted to ride up on said guide until it may pass into operative engagement with the keeper when it will drop by gravity to the position shown in Fig. 2. As best shown in Fig. 2, the outer margin of the bolt 20 is rounded so that when the door is moved endwise such rounded portion of the bolt will engage the keeper and the bolt thereby be lifted so that it will move into engagement with the keeper substantially in the manner just described.

As locks of this description are exposed to the elements it is desirable that means be provided for keeping the moving portions well lubricated, and to this end the case 14 is provided with a chamber 28 in its upper portion adapted to receive oily waste or other lubricating material. This chamber is provided with an opening 29 arranged in the path of the projection 21, which is adapted to enter it when the head 19 is moved to its uppermost position. When this occurs said projection receives oil or other lubricant from the chamber 28, and as the lubricant flows down over the latch it will be evident that whenever the latch is operated it will be lubricated, and consequently will not be apt to deteriorate because of moisture.

For locking the latch in operative position as well as for holding it out of operative

position when desired, a locking arm 30 is provided which is mounted at its upper end on a pivot 31 supported by bosses 32 which project from the case as best shown in Fig. 2. The shape of this locking arm 30 is best shown in Fig. 5 from which it will be seen that it comprises a vertical arm 33, the lower end portion of which is provided with a recess 34 adapted to receive the 10 operating arm 22 of the latch, and also a horizontal arm 35 which is adapted to move into alignment with a fixed flange 36 which projects laterally from the cover plate 37 of the case, as shown in Fig. 3. The parts 35, 15 36 are both perforated as shown at 38 in Fig. 5 so that a car seal may be passed through said openings, thereby sealing them together. The arm 35 and flange 36 are so placed that they register when the locking arm 30 is in its operative position shown 20 in Fig. 2, and since at that time the locking arm is in operative engagement with the operating arm 22 and the bolt 20 is projected into engagement with the keeper the application of the seal will prevent the lock 25 from being unlocked. When the device is used merely as a latch the locking arm 30 may be thrown over on top of the case, as indicated by dotted lines in Fig. 2, so that the latch may be freely operated. Preferably the car door is provided with two of these locks arranged near its opposite lower corners, as shown in Fig. 1, but if desired additional locks may be applied to the doors 30 at points higher up to support the door intermediately, as is desirable in the case of cattle cars, or where the door is subjected to considerable strain intermediately. Also it will be understood that in some cases it may 35 be desirable to apply the keeper to the door and the latch to the side of the car instead of the reverse arrangement shown in Fig. 1. As shown, the portion of the arm member 22 that projects from the casing is curved upward on an arc substantially concentric with the pivot of the locking arm 30 so that as such locking arm is moved into or out of operative position it is held in interlocked engagement with the arm 22 during the entire time that it is opposite such arm member 22. So curving the arm member 22 and recessing the adjacent face of the locking arm 30 permits not only a very strong interlocking of these parts but also enables such 40 two parts to lie in the space between the planes of the side walls of the casing, as clearly shown in Fig. 3.

If it be desired to secure the latch in its inoperative position, this may be accomplished by swinging the locking arm 30 down against the upper margin of the operating arm 22 so that the lower margin of the locking arm 30 rests upon said arm and holds the latch in the position shown in 45 dotted lines in Fig. 2.

Instead of using the locking arm 30 for the purpose of holding the latch out of operative position a swinging arm 39 may be employed for this purpose, as shown in Fig. 4, in which the arm 39 is mounted on a pivot 40 carried by a bracket 41, said arm being in such position that it is adapted to swing by gravity over the upper end of the operating arm 22, as shown by dotted lines in said figure. In Fig. 4 I have also shown a different form of locking arm which acts on the upper portion of the head 19 instead of on the operating arm 22. In this construction the locking arm comprises a shank 42 pivoted at its upper end on a pivot 43 and having an arm 44 which is adapted to swing through an opening in the case so that it overlies the upper portion of the head 19 when the bolt 20 is in its operative position. The shank 42 is also provided with a plate 45 which extends in a direction opposite to that of the arm 44 and is adapted to register with a plate 46 which projects from the margin of the case. The two plates 45, 46 are perforated to receive a car seal, as indicated by dotted lines in Fig. 4 and shown at 47 in Fig. 6. When the arm 44 is in its operative position, which it assumes by gravity, the bolt 20 is held projected since the head 19 cannot swing upward. The locking device 42 may be thrown up out of operative position, as indicated by dotted lines in Fig. 4, when it is not desired to use it. While my improved lock and latch is designed primarily for use on car doors it may be used in any other situation for which it is adapted, and the claims should be construed accordingly. I wish it to be understood also that my invention is not restricted to the specific construction shown and described as various modifications may be made without departing therefrom.

What I claim as my invention and desire to secure by Letters Patent, is—

1. The combination with a door, of a latch comprising a pivotally-mounted member having a downwardly-projecting bolt at one side of the pivot thereof and a curved operating arm projecting at the opposite side of said pivot, a keeper adapted to cooperate with said bolt, and a swinging arm movable into position to engage said curved arm and lock it in operative position, the pivot of said swinging arm being substantially concentric with the curvature of the operating arm.

2. The combination with a door, of a latch comprising a pivotally-mounted member having a downwardly-projecting bolt at one side of the pivot thereof and a curved operating arm projecting at the opposite side of said pivot, a keeper adapted to cooperate with said bolt, and a swinging arm movable into position to engage said latch and lock it in operative position, the pivot

- of said swinging arm being substantially concentric with the curvature of the operating arm.
3. The combination with a door, of a latch comprising a pivotally-mounted member having a downwardly-projecting bolt at one side of the pivot thereof and a curved operating arm projecting at the opposite side of said pivot, a keeper adapted to cooperate with said bolt, and a swinging arm movable into position to engage said operating arm for locking the latch in operative position, said swinging arm having means for interlocking it with said curved arm, and the pivot of said swinging arm being substantially concentric with the curvature of the operating arm.
4. The combination with a door, of a latch comprising a pivotally-mounted member having a downwardly-projecting bolt at one side of the pivot thereof and a curved arm projecting at the opposite side of the pivot, a keeper adapted to cooperate with said bolt, and a swinging arm movable along said curved arm and having a recess in one face to receive such curved arm, the pivot of said swinging arm being substantially concentric with the curvature of the operating arm.
5. The combination with a door, of a latch comprising a pivotally-mounted member having a downwardly-projecting bolt at one side of the pivot thereof and a curved operating arm projecting at the opposite side of said pivot, a keeper adapted to cooperate with said bolt, a swinging arm movable into position to engage said latch and lock it in operative position, and means associated with said swinging arm for sealing the latch in its operative position, the pivot of said swinging arm being substantially concentric with the curvature of the operating arm.
6. A latch comprising a case, a swinging latch member pivotally mounted therein and having a downwardly-projecting bolt at one side of the pivot thereof and an upwardly-curved operating arm projecting from the case at the opposite side of said pivot, and a locking arm pivotally mounted outside of the case above said curved arm and having means for detachably interlocking with said curved arm, the curvature of said curved arm being substantially concentric with the pivot of said locking arm. 45
7. A latch comprising a case, a swinging latch member therein, and means located over and operated by the swinging of said latch member for supplying lubricant thereto. 50
8. A latch comprising a case, a swinging latch member therein, a receptacle in the upper part of said case for containing lubricant, and means operated by the swinging of said latch member for supplying thereto lubricant from said receptacle. 55
9. A latch comprising a case, a pivotally-mounted latch member therein having a head at one side of the pivot thereof and an operating arm, and a receptacle in said case for lubricant, said receptacle having an opening lying in the path of said head whereby when said latch member is swung lubricant will be supplied thereto from said receptacle. 70
10. A latch comprising a case, a pivotally mounted latch member therein having a head at one side of the pivot thereof and an operating arm, a rib carried by said head, and a receptacle in said case for lubricant, said receptacle having an opening in the path of said rib whereby when said latch member is swung lubricant will be supplied thereto from said receptacle. 75
